UNITED STATES PATENT OFFICE.

FLORENT HINNEKENS, OF PATERSON, NEW JERSEY.

DEVICE FOR TREATING FABRICS WITH LIQUID.

Application filed May 2, 1928. Serial No. 274,400.

This invention relates to devices for discharging liquids against fabrics in the use of which the fabric is advanced in an upright path and the liquid is discharged from the device against the moving fabric. The principal object is to provide a device for the purpose indicated in the use of which the liquid stream delivered may be varied in force without its exceeding a certain degree, that is, be so forceful as not to soak the fabric well and perhaps to injure the same, and will be broad or flat and thin and of substantially equal volume throughout its breadth whatever its force.

In the drawing, Fig. 1 is a plan of the improved device; and

Figs. 2 and 3 are sections thereon on lines 2—2 and 3—3 of Fig. 1.

The device may be formed of sheet metal according to the present example.

1 and 2 designate an upper and a lower tubular part alined with each other and having a continuous space 3 between them; these parts form a passage A through which the fabric is passed in an upright path,—usually downwardly, wherefore the upper end of part 1 is shown flared to permit the fabric to be advanced through the passage without undue chafing.

Surrounding these parts and forming therewith a distributing chamber 4 is a cup-shaped receiver 5 whose bottom 5^a is apertured and receives and fits part 2 and whose upstanding wall 5^b reaches well above the slit or space 3; this receiver is open at the top, affording thereby an overflow outlet.

Slit 3 is horizontal.

Radial walls 6 are interposed between the passage-forming parts 1—2 and the wall 5^b of the receiver and each extends nearly to the top of part 1; one of these walls (the one at the right in Fig. 3) may extend clear to the bottom 5^a, but the others are spaced therefrom as shown in Figs. 2 and 3. The various parts may be secured together where they meet as by bending off an edge of one in each instance and riveting or welding the thus bent-off portion flat against the surface of the other, as at 7. One function of the walls 6 is to support the otherwise unsupported part 1.

Slit or space 3 is circumferentially continuous so that the liquid will flow inwardly into the passage as an unbroken sheet, wherefore the walls 6 are preferably recessed at 8 oppo-

site the slit thus leaving the same unobstructed.

An inlet 10 is provided in receiver 5 in its upstanding wall 5^b in registry with and below that wall 6 which is opposite the wall 6 which extends to the bottom wall 5^a, and to this inlet may be connected the supply means, as a pipe 11, as by fitting the pipe in the inlet. A shield traverses the receiver above the inlet and in the present case is in part formed by bending off the lower edge portion of the material forming the adjoining wall 6, as at 12, and in part by welding or otherwise securing a wing 12^a to the opposite side of said wall.

When the device is in use and the fabric is being advanced past the slit 3 the liquid admitted at inlet 10 will rise in the receiver until its level reaches the slit, whereupon it will issue into passage A as a broad flat sheet or stream of substantially uniform volume throughout its breadth because the slit is horizontal and of uniform width throughout; this stream will flow with variable force against the fabric depending upon the regulation of its flow by some valve in supply pipe 11, but such force will be limited upon the level of the liquid reaching the overflow outlet of the receiver. So that the level of the liquid in chamber 4 shall be the same all around, it is preferred that the liquid enter the chamber laterally, as shown, rather than upwardly or downwardly, which by causing disturbance would defeat this purpose; to the same end and for steadyng the liquid the two walls 6 which are in the example in planes transverse to pipe 11, while they extend below the slit and thus dip into the liquid and serve as baffles, extend short of the bottom of the receiver, but the wall 6 opposite said pipe is extended to said bottom so as to prevent any tendency of the liquid to swirl around the chamber when the same is annular, as in the example.

The overflow outlet being open all around permits access to the slit 3 for removing therefrom lint, fluff and other foreign matter which collects from the fabric and tends to clog the slit.

In that form herein shown, where the passage extends through the device, the latter may be more or less elongated so as to receive the fabric either in rope form or in flat (folded or fully extended) form.

There may be a trough 13 around the receiver to catch the overflow and a pipe 14 to conduct the same away.

Having thus fully described my invention, what I claim is:

1. A liquid discharging device having a liquid distributing chamber past which the fabric to be treated is to be advanced in an upright path close to said chamber, a horizontally elongated liquid delivery outlet from the chamber arranged at the side thereof adjoining said path and above the bottom of the chamber, means to supply liquid to the chamber, and an overflow outlet from the chamber arranged above the first-named outlet.
2. A liquid discharging device having an upright passage therethrough through which the fabric to be treated is to pass, a liquid distributing chamber extending around the passage, a horizontally elongated liquid delivery outlet from the chamber to said passage extending around the passage and arranged above the bottom of the chamber, means to supply liquid to the chamber, and an overflow outlet from the chamber arranged above the first-named outlet.
3. A liquid discharging device having a liquid distributing chamber past which the fabric to be treated is to be advanced in an upright path close to said chamber, a horizontally elongated liquid delivery outlet from the chamber arranged at the side thereof adjoining said path and above the bottom of the chamber, and means to supply liquid to the chamber, said chamber being open above the level of the slit and affording clear access to the same for substantially the full length of the slit.
4. A liquid discharging device having an upright passage therethrough through which the fabric to be treated is to pass, a liquid distributing chamber extending around the passage, a horizontally elongated liquid delivery outlet from the chamber to said passage arranged above the bottom of the chamber, means to supply liquid to the chamber laterally thereof, and a liquid-flow obstructing

wall extending upwardly from the bottom of the chamber substantially opposite said liquid supply means.

5. A liquid discharging device having a liquid distributing chamber past which the fabric to be treated is advanced, a horizontally elongated liquid delivery outlet from the chamber arranged at the side thereof adjoining said path and above the bottom of the chamber, means to supply liquid to the chamber, and a baffle extending upwardly in the chamber from a plane lower than said outlet and being spaced from the bottom of said chamber.

6. A liquid discharging device including upper and lower aligned tubular members forming an upright passage through which the fabric to be treated is advanced, said members having an endless space between them forming a liquid outlet to the passage, a receiver surrounding and forming a distributing chamber with the lower member and extending above said outlet-forming space, and means connecting the receiver and upper member and affording support for the latter, said receiver having means to supply liquid to said chamber.

7. A liquid discharging device including upper and lower aligned tubular members forming an upright passage through which the fabric to be treated is advanced, said members having an endless space between them forming a liquid outlet to the passage, a receiver surrounding and forming a distributing chamber with the lower member and extending above said outlet-forming space, and a wall connecting and traversing the space between the receiver and upper member and affording support for the latter, said wall leaving the outlet-forming space unobstructed and said receiver having means to supply liquid to said chamber.

In testimony whereof I affix my signature.

FLORENT HINNEKENS.
